TUFT-PILE-FABRIC LOOM.

Application filed October 20, 1926. Serial No. 142,868.

- This invention relates to looms for weaving tuft pile fabrics, such, for instance as Axminster or Moquette carpets or rugs and the like, wherein different yarns are taken 5 from a source of supply and passed about threads in the body fabric to form the tread surface thereof.
- In tuft pile fabric looms of this general type, the tuft forming yarn is wound upon 10 spools mounted in tube frames, which are connected to a carrier for moving the tube frames into the tuft yarn presenting position. In some instances the tube frames themselves are taken from the carrier by appropriate means to transfer the row of tufts 15 to the weaving point, and in other cases it has been proposed to withdraw the tuft yarn from the tube frames by grippers, cut off appropriate lengths of the tuft yarn and then cause the grippers to deliver the lengths 20 of tuft yarn to the weaving point or fell of the cloth. Looms of the former type are necessarily slow in operation and consequent production of fabric, and in the latter type, 25 wherein the tuft yarn is taken in lengths from the presenting mechanism and delivered to the weaving point or fell of the cloth, the character of mechanism employed has necessitated comparative slow movement 30 of parts in order that their paths of movement may not conflict.
- The present invention relates more particularly to the gripper type of tuft pile fabric looms and has for its object to provide 35 a loom of this character which may be run at high speed with consequent increased production and wherein the parts are so correlated and actuated that perfect tuft pile fabric may be produced.
- An important feature of the invention 40 contributing to these ends consists in a construction whereby the dents of the reed carried by the lay are moved in paths of non-intersection with the weft inserting means 45 whereby the weft may be inserted in the shed before the dents have been moved rearwardly back of the path of movement of the weft inserting means. Another equally important feature of the present invention consists in mounting the grippers for movement 50 in a backwardly and downwardly extending path through the warp threads to deliver the tuft yarn to the weaving point and then return the grippers to their upper position in a path of non-intersection with the path 55 of movement of the weft inserting means.
- One of the objections heretofore encountered in tuft pile fabric looms of the gripper type has been the liability of the grippers passing between the wrong warp 60 threads, and also the interference that may occur in the movement of parts as the grippers deliver the tuft yarn to the weaving point, and another important feature of the invention therefore consists in providing 65 means for insuring a proper guidance of the grippers in their movements to properly direct the ends of the grippers and the tuft yarns held thereby between their associated warp threads and the non-interference with 70 the reed dents. In this connection, also, the present invention contemplates guiding means for the reed dents so associated with the guiding means for the grippers that both the reed dents and grippers are maintained 75 in proper lateral relation during their respective movements.
- Another important feature of the present invention consists in mounting the grippers for movement in a backward and downwardly 80 extending path through the warp threads to lay the tuft yarn over the face of the breast comb with the trailing or free end of the tuft yarn extending downwardly, and thereupon moving the grippers in an upward direction to carry the held end of the tuft yarn adjacent the fell of the cloth to its proper position, so that upon the beat-up 85 movement of the dents, the weft thread is moved over the face of the comb to cause 90 the trailing end of the tuft yarn to be raised into its proper relation with the previously held end of the tuft yarn.
- The guiding means for the grippers and reed dents is of novel construction and serves 95 to laterally position these parts as well as the warp threads with which they are associated, so that perfect cloth shall be woven.
- Heretofore it has been the common practice to form the breast comb from a single 100 bar in which are cut a number of breast teeth, an operation both expensive and inaccurate in its results, and in accordance with another feature of the present invention the breast

comb is formed of separate breast teeth, whereby facility of manufacture is secured, and means are provided for holding such separate teeth in proper spaced relation on the breast beam.

It is desirable at times that one or more of the reed dents carried by the lay be removed, and the present invention provides means for readily accomplishing this end without disturbing the adjacent dents.

When the grippers have withdrawn the lengths of tuft yarn from the tube frames, a sliding bar provided with teeth along its edge is moved relative to the tuft yarn to engage them between the teeth of the bar, and a cutter has usually been mounted for movement transversely of the loom to shear or cut the tuft yarn held in the teeth of the bar. Heretofore the cutter has occupied its cutting position relative to the teeth of the bar, with the result that it prevents the adjacent tuft yarn from engaging the teeth of the bar, so that some of such tuft yarn may not be cut. In accordance with the present invention, however, the cutter or shearing knife is normally held in an inoperative position relative to the toothed bar to permit the tuft yarn to enter the teeth of the bar and upon movement of the cutter in its tuft-cutting operation, it is first moved into operative position relative to the teeth of the bar, with the result that all of the tuft yarn having been engaged between the teeth of the bar are severed during the cutting stroke of the cutter.

The invention, new features thereof, and novel combination of parts whereby increased production and high speed are attained, will best be made clear from the following description and the accompanying drawings of one good form of the invention.

In the drawings:

Fig. 1 is a side elevation of a tuft pile fabric loom, some of the parts being shown in section, containing the present invention;

Fig. 2 is an enlarged perspective view with some of the parts in section, showing the grippers, guides and reed dents in their associated relation;

Fig. 3 is an enlarged sectional detail showing the grippers moving to their upper tuft-taking position;

Fig. 4 is an end elevation showing the grippers as having gripped the yarn presented by the presenting mechanism;

Fig. 5 is a sectional elevation showing the grippers as having withdrawn lengths of tuft yarn from the presenting means and associated parts;

Fig. 6 is a sectional elevation showing the grippers as just releasing the tuft yarn preparatory to the return to their upper position;

Fig. 7 is a detached detail on an enlarged scale showing the gripper actuating mechanism;

Fig. 8 is a sectional detail showing the relation of the grippers and dents just before the grippers release the tuft yarn;

Fig. 9 is a sectional elevation showing the path of movement of the dents carried by the lay as they move backwardly in non-intersecting relation with the weft inserting means;

Fig. 10 is a similar view showing the dents as having been raised and moved forwardly during their beat-up movement;

Fig. 11 is an underside view showing the toothed bar and cutting mechanism for cutting the tuft yarn, the cutting mechanism being in its normal inoperative position;

Fig. 18 is a detail view of the dent positioning means at the bottom of the lay recess;

Fig. 19 is a horizontal section on the line 19-19 of Fig. 20; and

Fig. 20 is a vertical section on the line 20-20 of Fig. 19, showing the grippers as having released the tuft yarn during the beat-up movement of the dents.

The loom frame 1 may be of usual or convenient construction for supporting the operating parts and, as shown in the present instance of the invention, the loom frame is provided with the risers 2 which afford support for a carrier shaft 3 about which passes the carrier or chain 4 on which the tube frames are mounted. Each of the tube frames 5 has associated therewith one or more spools 6 on which may be wound the tuft yarn of appropriate color suitable for the pattern to be produced, as usual. The carrier or chain 4 may be given proper movements for presenting a tube frame in position for the tuft yarn extending therethrough to be taken by the grippers, but since the means for actuating the carrier form no part of the present invention and its actuating means being well-known, it is not herein illustrated. Each of the tube frames is provided with a tube 7 through which the tuft yarn carried by the tube frame extends.

The shedding mechanism for moving the

warp threads in the formation of the shed may be of usual character and as herein indicated comprises the frames 8 and heddles or the like having eyes 9 through which the 5 warp threads *a* pass. The shedding mechanism may be of any usual type and be actuated from any convenient source of power, but since the details of such mechanism form no part of the present invention and are now 10 well understood, they are not herein shown.

The weft inserting means indicated in Fig. 2 consists of a needle 10, as is common in this type of loom, and means are provided, though not here shown, because the details thereof 15 form no part of the present invention, for moving the weft inserting means or needle 10 through the shed formed by the shedding mechanism. As usual, the weft inserting mechanism or needle 10 inserts a double weft 20 *b* in the shed, but the particular means and number of weft inserted may be varied.

Mounted at the front of the loom is the breast beam 11 over which the tuft pile fabric *c* passes on its way to the take-up or toothed 25 roll 12.

The lay 13, Fig. 1, carries the dents 14 which extend upwardly therefrom in separated relation to beat up successive wefts, and is mounted for rocking movement on 30 the shaft 15. Extending downwardly from the lay 13 is the arm 16 connected to a rod 17 having a roll 18 which travels in the cam path 19 of the cam 20 mounted for rotative movement on the shaft 21, the construction 35 being such that as the cam rotates it will cause the lay 13 to rock on its shaft mounting 15 and actuate the dents 14.

The shaft 15 is mounted eccentrically in a rotating member or bushing 22 carried by 40 bearings 23 secured to the loom frame. The bushing 23 has secured thereto a gear 24, the teeth of which mesh with the teeth of the rack 25 guided for reciprocating movement in the lower part of the bearings 23 and connected at 26 with an arm 27 having a roll 28 which engages the cam path 29 in the cam 30 mounted for rotative movement on the shaft 21, the construction being such that the dents 14 are given a path of movement 45 as they retire from the fell of the cloth to carry the ends of the dents out of intersecting relation with the weft inserting means or needle 10. This characteristic movement of the dents is indicated in Figs. 8, 9 and 10 by 50 the dotted lines *d*, wherein it will appear that the dents move from beat up position in a downward and backward direction to carry the tops of the dents below the weft inserting means, as indicated in Fig. 9, so that before 55 the dents have reached a position backward of the path of movement of the weft inserting means, the latter may insert the weft without interference by the dents. The dents being in their backward position, as indicated 60 by full lines in Fig. 9, and the weft having

been laid in the shed, the dents are raised by the train of mechanism hereinbefore described, into the dotted line position indicated in Fig. 10, so that the front edge portions of the dents are back of the weft and on forward movement of the dents the weft is beaten into the fell of the cloth. 70

This enables the loom to be run at high speed because the weft inserting means does not have to delay its weft inserting movement until the dents have retreated backward into a position beyond the path of movement of the weft inserting means, or, in other words, the weft inserting means may be actuated to insert the weft into the shed as the 75 dents move from their beat-up to their rearward position.

In accordance with the present invention the grippers, of which there are a series, are moved from their tuft yarn taking position 80 in a backward and downward direction to carry the ends of the grippers and the tuft yarn held thereby below the warp threads and to lay the tuft yarn over the face of the comb, with the trailing end extending downwardly, as the gripped end of the tuft yarn is raised by the grippers above the warp threads. The tuft yarn being in the position stated and the dents moving forwardly 85 to the beat-up, the grippers release the held end of the tuft yarn, while the weft as it is beaten up, causes the downwardly extending free end of the tuft yarn to be moved upwardly over the face of the comb into the full beat-up position at the fell of the cloth. 90 In order to facilitate speed of operation of the loom and consequent increased production, the grippers are returned upwardly 95 through a backwardly and upwardly extending path different from the path of movement followed by the grippers as they carry the tuft yarn to the weaving point, and such return path of the grippers is non-intersecting with the path of movement of the weft inserting means, with the result that the weft 100 inserting means or needle 10 may insert the weft into the shed without interference by either the dents or the grippers in their inactive or return movements. 105

In tuft pile fabric looms of the gripper type the grippers are liable to become displaced as they move to carry the tuft yarn to the weaving point, and such displacement is liable to cause the grippers to pass between threads other than those between which they 110 are intended to pass, and also, in some cases, to contact with the dents. The present invention, therefore, contemplates means for guiding the grippers during their movements to maintain them in proper relation 115 with the warp threads through which they are to pass, and also with respect to the dents carried by the lay, and inasmuch as the grippers and dents approach the weaving point 120 carried by the lay, and inasmuch as the grippers and dents approach the weaving point 125 or fell of the cloth in slightly different lat- 130

eral paths, the guiding means referred to is preferably constructed to guide not only the grippers in their movements but also the dents.

Having reference more particularly to Figs. 2, 19 and 20, the means for guiding the grippers and dents consists of guiding members, of which there is a series, between which the grippers and the dents move. In the particular construction shown, the guiding means consists of the plates 31 secured to the loom frame and extending frontwardly preferably to or beyond the face of the breast comb. Since the dents are guided in a path laterally separated from the path of movement of the grippers, the guiding plates 31 are preferably formed of bent sheet metal having a lower portion 32 wherein the metal is doubled upon itself, as indicated in Fig. 19, thereby producing a guide 33 in which the dents 14 move towards and from the fell of the cloth, and between the several plates 31 a guideway 34 is provided for guiding the grippers in their movements towards and from the weaving point, the effect being that the dents and the grippers are accurately maintained in their desired paths of movement without interference and for directing the grippers between the proper cooperating warp threads. In order that the warp threads *a* may also be guided in a path laterally of the grippers, each of the guide plates 31 is provided with an opening 35 through which the warp threads, usually three, pass on their way from the usual warp beam or warp supply to the weaving point or fell of the cloth. The effect of this is indicated in Fig. 19, wherein it will be noted that the warp threads *a* are passed laterally through the openings 35 and consequently lie closely to the surface of the guide-plates 31, thus maintaining the warp threads in proper relation with the grippers which are to pass between them. From the construction described, as one form of this feature of the invention, it will be apparent that the warp threads, the grippers and the dents are guided in their respective paths in correlated relation with each other and separated from each other laterally, so that all danger of interference either by the dents or by the grippers with each other or the warp threads is avoided.

The guide plates 31 may be secured to the loom frame in appropriate manner, but as herein shown, they are mounted upon cross-beams 36 and 37 extending transversely of the loom frame, and are held in spaced relation by the spacers or racks 38, which may be formed with spacing teeth 39 between which the plates are seated. The frontwardly extending end portions of the guideplates 31 are secured in place by locks which maintain the guideplates seated in the spacers 38. The guideplate locks may be variously contrived, but in the present instance of the invention

they are formed as flat plates 41 provided with a series of slots 42 along one edge, and when turned into a horizontal position registering with the horizontal slots 40 in the guideplates, said locks may be entered transversely through said openings and then turned downwardly to embrace within the slots 42 the several guideplates which are thus held in spaced relation and locked in their seats or spacers 38. From the construction described it will appear that the guideplates are held in proper spaced relation and locked in position, and yet are capable of being removed by manipulation of the lock when it becomes necessary for repairs or other purposes.

Inasmuch as the guideplates 31 guide not only the grippers but also the dents in the preferred form of the invention, the guideplates 31 are each provided with an opening 43 which openings are alined transversely of the loom when the guideplates are in position, for the passage of the weft inserting means or needle 10, as indicated in Fig. 2.

It is believed that the present invention affords the first instance in the art of grippers for taking lengths of tuft yarn from the tuft yarn presenting mechanism and guiding the movement of the grippers to the weaving point, and it is also believed that applicant is the first to provide guiding means for the grippers and dents to maintain these parts in their respective paths of operation, so that while the above form of guiding means affords a good practical instance thereof, it is to be understood that the guiding means may be variously contrived to effect the results hereinbefore noted.

The grippers for taking lengths of tuft yarn from the tuft yarn presenting mechanism and delivering them to the weaving point are mounted for movement in a backwardly and downwardly extending path, as hereinbefore described, and comprise the gripper shaft 44 (Figs. 2, 3, 4, 5, 6 and 7) which has affixed thereto the gripper jaws 45. In the present instance of the invention, the gripper shaft 44 is provided with a series of slots 46 into which the heel portions 47 of the grippers 45 extend, and the grippers 45 are held therein by suitable means, such, for instance, as the headed bolts 48, the head portions of which enter recesses 49 formed in the heel portions of the grippers, as indicated in Figs. 2, 3 and 7, the effect being that the gripper jaws 45 are substantially rigid with the gripper shaft 44 and held in spaced relation.

The gripper shaft 44 is mounted eccentrically in rotative bearings or bushings 50 supported in bearing blocks 51, one at each side of the loom, and each rotative bearing or bushing is provided with a gear 52 which is actuated by a toothed rack 53 for the purpose of turning the rotative bearing or bush-

ing to bodily raise or lower the gripper shaft at desired times, as will later appear.

The gripper shaft 44 is itself mounted for rotative movement and for this purpose has secured thereto a gear 54, Figs. 2 and 7, which may be enclosed in a casing 55, as indicated. The gear 54 is actuated by a toothed rack 56 to cause rotative movement of the gripper shaft to carry the grippers from their tuft 10 yarn receiving position to the tuft yarn delivering position at the weaving point and back.

The means for actuating the gripper shaft and rotative bearing or bushing may be varied, but in the present instance of the invention a shaft 57 extends transversely of the loom (Fig. 1), and is mounted in suitable bearings and to the shaft 57 is secured a gear 58 which meshes with the gear 59 secured to the shaft 21 below, it being understood that the shaft 21 is given rotative movement from a suitable source of power, to the effect that both the shaft 21 and the shaft 57 will be rotated.

Secured to the shaft 57 is a cam 60 (Fig. 1) having a cam path 61 in which is received a roller 62 connected with the toothed rack 56 for operating the gripper shaft 44, as hereinbefore described, to move the grippers 30 in their backwardly extending path towards and from the weaving point.

Also mounted on the shaft 57 is the cam 63 having the cam path 64 which receives a roller 65 secured to the toothed rack bar 53, by which the rotative bearing or bushing 50 is given rotative movement for the purpose of bodily raising or lowering the grippers, as will hereafter more fully appear.

Keyed or secured to the gripper shaft 44 are the arms 66 in which is mounted for rotative movement the gripper closing shaft 67 (Fig. 7). The gripper closing shaft 67 has a series of longitudinally extending teeth 68 (Fig. 2) which are engaged by teeth 69 on the gripper closing jaws 70 which are or may be pivotally connected to the gripper jaws 45 at 71, the construction being such that should the gripper closing shaft 67 be rotated clockwise, as in Figs. 2 and 7, the gripper closing jaws 70 will close upon the gripper jaws 45, a condition which occurs when the grippers are in their upper tuft 50 yarn gripping position.

Secured to the gripper closing shaft 67 is an arm 72 which extends laterally therefrom and is normally under the influence of a spring 73 which, when the gripper closing shaft 67 is free to rotate, will actuate the gripper closing shaft to open the grippers, and conversely, when the arm 72 is moved against the tension of the spring 73, it will rotate the gripper closing shaft 67 to cause the grippers to close.

Extending from the hub portion of the arm 72 is a shoulder 74 adapted to be engaged

by a lock or catch to maintain the grippers closed when the arm 72 has been moved against the tension of its spring 73. In the present instance of the invention, the lock comprises an arm 75 pivotally mounted at 70 76 on a collar 77 secured to the gripper shaft 44, and said arm is provided with a locking shoulder 78 adapted to engage with the shoulder 74 of the arm 72 under the influence of a spring 79 when the gripper closing arm 72 75 has been rotated to close the grippers. Thus, when the grippers have been closed, as will hereinafter appear, the lock maintains the grippers in closed gripping position until the lock is tripped.

The gripper closing and lock tripping means is best indicated in Fig. 1, and comprises a trip arm 80 pivotally mounted on the riser 2 at 81, having a backwardly extending portion which carries a roll or pin 82 adapted to ride upon the periphery of a cam 83 secured to the shaft 57. The roll 82 is normally maintained in engagement with the cam 83 by a spring, such, for instance, as the spring 84, Fig. 1, one end of which is secured to a fixed point as at 85 and the other end of which is connected to the forwardly extending arm of the trip lever 80, as at 86. The forwardly extending arm of the trip lever 80 is provided with a tripping portion 87 which is adapted to engage at times with the arm 72 and with the lock lever 75.

Assuming the grippers in the position indicated in Fig. 3, wherein they are being moved in their forwardly and upwardly 100 extending path towards the tuft yarn presenting mechanism, as indicated by the arrow, it will be noted that the lock is tripped and the gripping jaws are open ready to receive the tuft yarn from the presenting mechanism. 105 From this point the gripper shaft and parts carried thereby, including the closing gripper jaws, are moved upwardly by rotation of the rotatable bearing or bushing 50, as hereinbefore described, and the grippers assume an upward position with the tuft yarn between the gripper jaws. At this time the gripper closing arm 72 is actuated by the lever 80, which as before stated, is operated from the cam 83, the effect being that the arm 80 depresses the gripper closing arm 72 and rotates the gripper closing shaft 67, whereupon, 110 the grippers grip the yarn, as indicated in Fig. 4, and the shoulder 78 of the arm 75 engages the projection 74 on the hub of the gripper closing arm 72 and effectively locks the grippers closed upon the tuft yarn.

When the grippers have thus gripped the tuft yarn, they will move downwardly to withdraw lengths of the tuft yarn from the tuft yarn presenting mechanism by rotation of the rotatable bearing or bushing 50 through the train of mechanism described, and the parts take the position indicated in Fig. 5. The gripper shaft 44 is now rotated to carry 115 120 125 130

- the grippers from the position indicated in Fig. 5, where the tuft yarn has been cut or severed from the presenting mechanism to deliver the tuft yarn to the weaving point.
- 5 The path of movement of the grippers in carrying the severed tuft yarn from the presenting mechanism to the weaving point is indicated by the dash and dot line *x* in Fig. 1, wherein it will be noted that the ends of 10 the grippers are passed backwardly and downwardly through the warp. From this point the grippers are moved frontwardly and upwardly and carry the gripped end of the tuft yarn above the warp threads, while 15 the trailing end thereof rests upon the face of the breast comb, as indicated in Fig. 14. The weft having been laid in the shed by the weft inserting means, the dents 14 move frontwardly towards the fell of the cloth 20 carrying the weft threads against the tuft yarn at the top of the comb, and upon further frontward movement of the dents 14 the grippers release the ends of the tuft yarn adjacent the fell of the cloth and the trailing 25 end of the tuft yarn is pushed frontwardly over the inclined face of the breast comb upwardly through the warp threads to form the completed tuft loop, as indicated in Fig. 6.
- The gripper release is effected by the lever 30 80, which, as indicated in Fig. 6, trips the lock 75 just prior to the full beat-up movement of the dents and then the grippers are returned to upper position for another supply of tuft 35 yarn.
- As hereinbefore noted, it is desirable that the weft presenting means shall be free to insert the weft without interference by the grippers on the return movement to their upward position for another supply of tuft 40 yarn, and for this purpose the gripper shaft 14 is rotated in the opposite direction to carry the grippers in an upwardly and backwardly extending path in non-interference with the path of movement of the weft inserting 45 means, as indicated by dot and dash line *y*, Fig. 1, the effect being that as the grippers are moved upwardly and as the dents are moved rearwardly, the weft inserting means may be actuated without waiting for these 50 parts to pass its path of movement, thus contributing to increased speed of the loom and increased cloth production.
- In order to properly position the tuft yarn 55 and correlate the grippers therewith as they seize the tuft yarn in their upper position, the present invention provides positioning blades which are mounted upon the slide 88, Figs. 1 and 2, and connects the slide to actuating means for moving the slide towards the 60 tuft yarn presenting position as the grippers rise to take the yarn. One appropriate means for effecting the movement of the slide consists of a guide 89 in which the slide is mounted for sliding movement. Connected

to the slide is a rod 90, Fig. 1, which extends 65 rearwardly and is connected at 91 with a lever 92 pivotally mounted at 93 and normally held in its forward position against the cam 94 by means of a spring 95. The cam 94 may be appropriately secured to the shaft 57 to effect 70 frontward movement of the slide and the blade positioning devices and to again permit the slide to retreat under the action of the spring 95.

Mounted upon the slide 88 is a transversely 75 extending bar 96 in which the positioning blades are held. The bar 96 is provided with a transversely extending channel 97, Fig. 2, in which is secured the positioning rack 98 having upwardly extending spaced teeth to 80 receive between them the backwardly extending positioning blades 99 to thereby properly space the positioning blades, and in order to hold the blades and rack in operative engagement a cover plate 100 may be appropriately secured to the bar 96 and bear directly upon the top edge portion of the positioning blades, the lower edge portions of which are preferably bevelled, as indicated at 101, Fig. 12, the effect being that when the slide 88 is moved 85 rearwardly, the positioning blades 99 enter between the tuft tubes of the presenting mechanism and position the tuft yarn for seizure by the grippers.

Also mounted upon the slide 88 is a plate 95 102, Fig. 2, which is preferably secured between the bar 96 and the top of the slide, and the front edge portion of the plate 102 is provided with a series of teeth 103, Figs. 11, 12 and 13, the spaces of which correspond to the 100 spaces between the blades 99, the effect being that as the slide is moved rearwardly, the tuft yarn extending from the tuft yarn presenting tubes be held securely in the teeth 103 of the plate 105 which, as it moves backwardly, is liable to 110 displace the yarn, and to this end, the grippers, which now have seized the yarn, are given a slight forward movement to deflect the tuft yarn out of a vertical line frontwardly towards the teeth of the plate 102 and 115 securely position it therein.

Heretofore it has been common to provide cutting mechanism for severing the yarn drawn from the presenting mechanism by the grippers and such cutting mechanism has usually been maintained in its operative cutting position so that when it is moved transversely of the loom it may cut or sever the tuft 120 yarn between the tubes and the grippers. In accordance with the present invention, the cutting mechanism is given a similar movement transversely of the loom, but the cutter itself is normally held in an inoperative posi- 125

tion when it is idle, in order that the tuft yarn opposite thereto may be properly positioned in the teeth of the plate 102.

Mounted upon the slide 88 for movement transversely of the loom is the cutter carriage 104 on which is mounted the tuft yarn cutter, as indicated in Figs. 11, 12 and 13. In the present instance of the invention, the cutting blade 105 is carried by an arm 106 pivotally mounted at 107 to the carriage 104, and connected with the arm 106 on which the cutter is mounted is the cutter actuating means which consists of mechanism for imparting to the cutter and cutter carriage the active cutting stroke. This operating mechanism may be variously contrived and as indicated in the present instance of the invention, may be a flexible member, such as a rope or the like 108, secured to the pivoted arm 106 at 109, and extending to the opposite side thereof, as indicated at 110. When the cutter carriage has been moved transversely of the loom to cut the tuft yarn, it is returned to its initial position at the opposite side of the loom by means of the portion 110 of the cutter actuating mechanism, and since such portion is connected to the swinging arm 106, the cutter itself is swung or moved from its operative to an inoperative position, so that the rear end of the cutter is within the line of teeth 103 formed on the plate 102. When the tuft yarn is to be cut, the portion 108 of the cutter actuating mechanism first effects movement of the cutter to its operative or outer position with respect to the teeth 103 and upon movement of the carriage transversely of the loom, all of the tuft yarn is cut.

From the above it will be noted that the tuft yarn cutter is normally held in an inoperative position relative to the teeth of the toothed plate 102, so that the tuft yarn may be properly positioned in the teeth 103 for the cutting operation without interference by the cutter itself. A spring 111 serves to hold the cutter 105 closely against the bottom of the toothed plate 102 and may be secured to the arm 106 by a screw 112 and adjusted as to its tension by the adjusting hand piece 113.

It has been customary heretofore in tuft pile fabric looms to provide a breast comb by cutting a bar to form rearwardly projecting teeth, but such formation of the breast comb detracts from accuracy of its formation and is objectionably expensive. One of the features of the present invention, therefore, is to provide a breast comb which shall be formed of a number of separate and independent teeth relatively positioned on the breast beam and held in assembled relation by comb teeth securing means.

In accordance with the present invention, the breast comb is formed of a plurality of separate teeth 114, Fig. 16, which may be readily fabricated or cut from appropriately sized sheet material. Each comb tooth has a

tuft yarn receiving face 115 which extends upwardly and frontwardly of the tooth and is provided on one of its edge portions, which extend frontwardly, with means for cooperating with the teeth holding devices. In the present instance of the invention, each tooth 114 is provided with an upwardly extending lug 116, Fig. 16, which may be formed by cutting out recesses 117 at each side thereof; the precise form of such detail, however, is not material, the essential being that the teeth of the breast comb be made separate and independent of each other and held in spaced relation upon the breast beam. In the present instance of the invention, the breast beam is provided with a recess 118, Fig. 14, and in the bottom of the breast beam recess is the spacer 119 for properly spacing the separate teeth in their correlated position to form the breast comb. In the present instance the spacer comprises a rack 120 from the bottom portion of which extend the upward projecting lugs 121 forming spaces therebetween for the reception of the individual and separate teeth of the comb. The spacer may be secured in the recess of the breast beam by suitable means, such as the screw 122.

Overlying the separate comb teeth 114, as shown, is a cover plate 123 held to the breast beam by securing means, such as the screw 124, and such cover plate is provided with an interlocking recess 125 into which may project the lug 116 extending from the individual comb teeth, the construction being such that the individual or separate comb teeth are held upon the breast beam in spaced relation and secured thereto by means connected to the breast beam itself. Not only does the construction described provide a cheap and effective manner of forming the breast comb, but the accuracy of the comb teeth is insured to a far greater extent than is the case when the comb teeth are formed in a comb bar by kerfs cut therein.

As hereinbefore indicated, the lay 13 carries a series of dents for beating up the successive weft threads as they are laid in the shed, and since the dents sustain the full blow of the beat-up movement they must be securely and accurately positioned on and held to the lay. It becomes desirable at times to remove one or more of the dents from the lay, either for repair or other purposes, or for varying the gage of the reed formed by the dents, and the present invention provides an effective and simple means for this purpose.

In accordance with the present invention, the lay 13, Fig. 14, is provided with a recess 126 for receiving the heel portions 127 of the dents, each of which has the shoulder portion 128 which rests upon the top of the rear wall of the recess, to thereby sustain the blow of the beat up. The dents 14 are formed separately and are positioned in the recess 126.

of the lay by means of spacers 129 each of which may be formed as indicated in Fig. 17; that is, the spacers 129 may be formed of sheet material provided with a series of teeth 130 extending from an edge portion thereof, of such gage as desired for the dents. The heel portion 127 of each dent is received in the opening between the teeth 130 of the spacers, thereby properly spacing the dents in their relation to each other. In the lower part of the lay recess 126 is a spacer 131 which may extend into the material of the lay and project upwardly as indicated in Fig. 14. The upwardly extending edge portion of the spacer 131, a section of which is indicated in Fig. 18, is provided with teeth 132, the upper edge portions of which are preferably bevelled, as indicated, and the heel portion 127 of the dents is provided with a recess 133 which straddles the body portion of the spacer 131 when the heel portion 127 is engaged between the teeth of the spacer. It may be desirable to form the spacers of sheet material in some instances, and in such case the spacers 129 may be provided with downwardly extending flanges 134 to overlap the front and rear faces of the lay, and such spacers may be secured to the lay by means such as the screws 135.

30 The spacers as thus far described maintain the dents in their separated and spaced relation, and in order that they may be held seated in the recess of the lay reed removable therefrom, the present invention contemplates locking means for the dents. In the present instance of the invention, the heel portion 127 of each dent is provided with a recess at one upwardly extending edge thereof, as indicated at 136, and the locking key 40 137 has a projection 138 to engage the recess 136. In order to accommodate the locking key 137, the adjacent wall of the lay recess is cut away as at 139 and the locking key extends upwardly in the recess to a point substantially adjacent to and underlying one of the spacers 129.

The locking keys 137 are preferably formed in short sections or lengths and may be held in operative engagement with the dents by means such as the screw or screws 140, the construction being such that upon backing off the key holding means or screws 140, any section of the locking keys may be released from the recesses 136 of the dent heels, so that by 50 simple upward movement of a dent at such time, the inclined walls of the recess 136 and the projection 138 of the key enable anyone of the dents to be lifted out of the lay.

What is claimed is:

60 1. In a tuft pile fabric loom, the combination of weft inserting means, grippers for taking tuft yarn from a source of supply and delivering such yarn at the weaving point, the lay provided with dents to beat up the weft on forward movement of the lay, and

means for causing the dents and grippers to be moved in a path non-intersecting with the path of movement of the weft inserting means during the idle movement of the grippers and lay to permit insertion of the weft during such idle movements whereby increased speed of production of a tuft pile fabric is secured.

2. In a tuft pile fabric loom, the combination of weft inserting means, grippers for taking tuft yarn from a source of supply and delivering such yarn at the weaving point, the lay having a series of dents mounted thereon to beat up the weft on forward movement of the lay, and means for imparting backward movement of the lay and grippers in a path non-intersecting with the path of movement of the weft inserting means to permit insertion of the weft during backward movement of the grippers and lay that increased production of the tuft pile fabric may be secured.

3. In a tuft pile fabric loom, the combination of weft inserting means, individual grippers for taking tuft yarn from a source of supply and delivering such yarn at the weaving point, the lay having a series of dents extending therefrom to beat up the weft on forward movement of the lay, and means for causing the grippers and dents to be moved bodily in their idle stroke in a path non-intersecting with the path of movement of the weft inserting means to permit insertion of the weft before the dents and grippers have moved beyond the weft inserting means.

4. In a tuft pile fabric loom, the combination of weft inserting means, grippers for taking tuft yarn from a source of supply and delivering such yarn at the weaving point, the lay having a series of dents extending therefrom to beat up the weft on forward movement of the lay, and means for bodily lowering the dents and raising the grippers into paths non-intersecting with the path of movement of the weft inserting means as the lay and grippers are moved from the weaving point to permit insertion of the weft at any time during the idle movements of the lay grippers.

5. In a tuft pile fabric loom, the combination of weft inserting means, grippers for taking tuft yarn from a source of supply and delivering such yarn at the weaving point, the lay having a single series of dents for beating up the weft on forward movement of the lay, and means for causing the dents and grippers to be moved backwardly in paths non-intersecting with the path of movement of the weft inserting means that the weft may be laid in the shed during backward movement of the grippers and lay.

6. In a tuft pile fabric loom, the combination of the lay, a series of dents mounted thereon to beat up the successive weft threads as they are laid in the shed, grippers for taking tuft yarn from a source of supply and

- delivering such yarn at the weaving point, and means for raising the grippers and lowering the dents bodily out of the path of the weft inserting means as the lay and grippers 5 move in their idle stroke to permit inserting of the weft into the shed before the dents and grippers have moved backward beyond the path of the weft inserting means.
7. In a tuft pile fabric loom, the combination of the lay, a series of dents mounted thereon to beat up the successive weft threads as they are laid in the shed, grippers for taking tuft yarn from a source of supply and delivering such yarn at the weaving point, 10 and means for bodily raising the grippers and moving the dents downwardly as they are moved away from the weaving point to permit the insertion of the weft, then returning the grippers and dents in a different path 15 to the weaving point.
8. In a tuft pile fabric loom, the combination of weft inserting means, the lay, a single series of dents mounted thereon to beat up the successive weft threads as they 20 are laid in the shed, grippers for taking tuft yarn from a source of supply and delivering such yarn at the weaving point, means for imparting a substantially elliptical movement to the dents, the lower element of the 25 ellipse being traversed by the dents on backward movement of the lay to permit insertion of the weft without interference by the dents as they move backwardly and means for bodily moving the grippers upwardly from the 30 weaving point and then backwardly in a path non-intersecting with the path of the weft inserting means.
9. In a tuft pile fabric loom, the combination of weft inserting means, the lay, a series of fixed dents extending from the lay 35 to beat up the successive weft threads laid in the shed, grippers for taking tuft yarn from a source of supply and delivering such yarn at the weaving point, and means for imparting to the lay a downward and backward movement to cause the dents to dip below the path of movement of the weft inserting means as the lay goes back and means for bodily raising the grippers from the 40 weaving point above said path and then moving them in non-intersection with the weft inserting means as the grippers are returned to take a fresh supply of tuft yarn.
10. In a tuft pile fabric loom, the combination of weft inserting means, the lay provided with dents to beat up the weft on forward movement of the lay, means for causing the dents to be moved in a path non-intersecting with the path of movement of the 45 weft inserting means on backward movement of the lay to permit insertion of the weft before the dents have moved backward beyond the path of the weft inserting means whereby increased speed of production is secured, and 50 guides for guiding the dents in their movements.
11. In a tuft pile fabric loom, the combination of weft inserting means, the lay provided with dents to beat up the weft on forward movement of the lay, means for causing the dents to be moved in a path non-intersecting with the path of movement of the weft inserting means on backward movement of the lay to permit insertion of the weft before the dents have moved backward beyond the path 55 of the weft inserting means whereby increased speed of production is secured, and guide elements between which the dents travel in their movements.
12. In a tuft pile fabric loom, the combination of weft inserting means, the lay having a series of dents, means for imparting movements to the lay to cause the dents to beat up successive weft threads laid in the 60 shed by the weft inserting means, and guide elements for the dents for preserving proper position of the dents during lay movements.
13. In a tuft pile fabric loom, the combination of weft inserting means, the lay having a series of dents, means for imparting movements to the lay to cause the dents to beat up successive weft threads laid in the shed by the weft inserting means, and guide elements 65 extending frontwardly on the loom between which the dents travel during their movements.
14. In a tuft pile fabric loom, the combination of weft inserting means, the lay having a series of dents to beat up the weft laid in the 70 shed, and guide plates secured to the loom frame and extending frontwardly towards the breast beam for guiding the movements of the dents.
15. In a tuft pile fabric loom, the combination of weft inserting means, the lay having a series of dents to beat up the weft laid in the 75 shed, a comb mounted at the front of the loom, and guide elements extending from a point rearward of the lay to the comb for directing the movements of the dents.
16. In a tuft pile fabric loom, the combination of weft inserting means, the lay having a series of dents to beat up the weft laid in the 80 shed, guide plates for guiding the dents in their movements and provided with openings for the passage of the weft inserting means.
17. In a tuft pile fabric loom, the combination of the lay having a series of dents to beat up successive weft threads laid in the shed, weft inserting means, a series of guides for guiding the dents in their paths of movement and provided with passageways for the weft inserting means, and means for moving the dents downwardly below the path of the weft 85 inserting means as the lay moves back.
18. In a tuft pile fabric loom, the combination of a series of grippers for taking short 90

lengths of tuft yarn from a source of supply and delivering them at the weaving point, means for operating the grippers, and guide plates for directing the movements of the grippers in their delivery of the tuft yarn to the weaving point.

19. In a tuft pile fabric loom, the combination of grippers for taking short lengths of tuft yarn from the source of supply and delivering them at the weaving point, means for cutting the tuft yarn from the source of supply, means for operating the grippers, and gripper guiding elements between the gripper supports and the ends thereof for guiding the grippers in their movement to the weaving point.

20. In a tuft pile fabric loom, the combination of the lay having dents to beat up the weft laid in the shed, grippers for taking short lengths of tuft yarn from a source of supply and delivering them at the weaving point, means for operating the grippers, and plate guides for correlating the grippers and dents in their respective movements.

21. In a tuft pile fabric loom, the combination of the lay having dents to beat up the weft laid in the shed, grippers for taking lengths of tuft yarn from a source of supply and delivering them at the weaving station, guiding elements disposed between the grippers for guiding the grippers in their movement to the weaving station, and guiding elements between the dent support and the ends of the dents for guiding the dents in their beat up movement, said guiding elements acting to properly correlate the grippers and dents during weaving.

22. In a tuft pile fabric loom, the combination of the lay having dents to beat up the weft laid in the shed, grippers for taking lengths of tuft yarn from a source of supply and delivering them at the weaving station, and guiding elements for the dents laterally of the guiding elements for the grippers to guide the grippers and dents in non-interfering paths.

23. In a tuft pile fabric loom, the combination of the lay having dents to beat up the weft laid in the shed, weft inserting means for inserting weft into the shed, grippers for taking lengths of tuft yarn from a source of supply and delivering them at the weaving point, and guiding plates for the grippers and dents for guiding them in non-conflicting paths during their respective movements.

24. In a tuft pile fabric loom, the combination of the lay having dents to beat up the weft, weft inserting means, grippers for taking lengths of tuft yarn from a source of supply and delivering them at the weaving point, and guiding means for the grippers and dents for guiding them in non-interfering paths during their movements to the weaving point.

25. In a tuft pile fabric loom, the combina-

tion of the lay having dents, guiding means for the dents during their beat up movement towards the weaving point, grippers for taking lengths of tuft yarn from a source of supply and delivering them at the weaving point, and gripper guiding means for guiding the grippers laterally of the cooperating dents in their movements to the weaving point.

26. In a tuft pile fabric loom, the combination of a series of grippers mounted to swing in a backwardly extending path to take tuft yarn from a source of supply and deliver them at the weaving point, and plate guiding means for guiding the grippers in their backwardly extending path as they move to the weaving point.

27. In a tuft pile fabric loom, the combination of a series of grippers mounted to swing in a backwardly extending path to take tuft yarn from a source of supply and deliver them at the weaving point, and guiding means for guiding the grippers in their backwardly extending path as they move to the weaving point, the lay having a series of dents, and guiding means for the dents, said guiding means for the grippers and dents serving to prevent contact of the grippers and dents as they move towards the fell of the cloth.

28. In a tuft pile fabric loom, the combination of a series of tuft yarn spools, a carrier for the spools, grippers for taking lengths of tuft yarn from the spools and delivering them at the weaving point, and gripper guides extending between the tuft yarn carrier and weaving point for directing the path of movement of the grippers.

29. In a tuft pile fabric loom, the combination of a series of tuft yarn spools, a carrier for the spools, grippers for taking lengths of tuft yarn from the spools and delivering them at the weaving point, and gripper guiding plates forming guides for each gripper as it moves to the weaving point.

30. In a tuft pile fabric loom, the combination of the lay having dents to beat up the weft laid in the shed, weft inserting means, grippers mounted to travel in a backwardly extending path to take lengths of tuft yarn from a source of supply and carry them between the warp threads, and means extending between the source of supply and warp threads for guiding the grippers to properly correlate each gripper with respect to the warp threads as the grippers deliver the tuft yarn.

31. In a tuft pile fabric loom, the combination of the breast comb, the lay having dents to beat up the weft, weft inserting means, grippers for taking lengths of tuft yarn from a source of supply, and means for operating the grippers to pass the gripped ends thereof below the warp threads and then raise the gripped ends to lay the free backwardly extending ends of the tuft yarn over the face

of the comb and carry the held end of the tuft yarn above the comb.

32. In a tuft pile fabric loom, the combination of the breast comb, the lay having dents to beat up the weft, weft inserting means, grippers for taking lengths of tuft yarn from a source of supply, and means for moving the grippers in a backwardly and downwardly extending path to pass through the warp threads, lay the free end of the tuft yarn over the face of the comb and carry the held end of the tuft yarn above the comb.

33. In a tuft pile fabric loom, the combination of the breast comb, the lay having dents to beat up the weft, weft inserting means, grippers for taking lengths of tuft yarn from a source of supply, and means for moving the grippers in a backwardly and downwardly extending path to pass through the warp threads, lay the free end of the tuft yarn over the face of the comb and carry the held end upwardly adjacent the fell of the cloth above the warp threads.

34. In a tuft pile fabric loom, the combination of the breast comb, the lay having dents to beat up the weft, weft inserting means, grippers for taking lengths of tuft yarn from a source of supply, and means for moving the grippers in a backwardly and downwardly extending path to pass through the warp threads, lay the free end of the tuft yarn over the face of the comb and carry the held end upwardly adjacent the fell of the cloth above the warp threads, and means for guiding the grippers during such movements.

35. In a tuft pile fabric loom, the combination of the lay having dents to beat up the weft thread, the breast comb, weft inserting means, a series of grippers for taking lengths of tuft yarn from a source of supply, and means for operating the grippers to lay the free ends of the tuft yarns in a backwardly extending direction from the fell of the cloth on the face of the comb and carry the held end upwardly adjacent the fell of the cloth, and guides for directing the movements of the grippers and dents in non-interfering paths.

36. In a tuft pile fabric loom, the combination of the lay having dents to beat up the weft, shed forming mechanism, weft inserting means for inserting weft in the shed, the breast comb, grippers for taking lengths of tuft yarn from a source of supply and delivering them to the weaving point, means for moving the grippers in a backwardly and downwardly direction to carry the tuft yarns through and below the warp threads and then in an upward direction to withdraw the grippers from the warp threads and lay the tuft yarn on the face of the comb with the free end extending downwardly, and means for freeing the tuft yarn from the grippers as the lay beats up the weft.

37. In a tuft pile fabric loom, the combina-

tion of the lay having dents to beat up the weft, the breast comb, shed forming mechanism, weft inserting means, a series of grippers for taking lengths of tuft yarn from a source of supply, means for moving the grippers in a backward and downward direction to pass the tuft yarn through and below the warp threads, then in an upward direction to carry the gripped ends of the tuft yarn above the warp threads with the trailing ends extending downwardly over the face of the comb and moving the grippers in a backward and upward direction for another supply of tuft yarn.

38. In a tuft pile fabric loom, the combination of shed forming mechanism, weft inserting means, grippers for taking lengths of tuft yarn from a source of supply and delivering them at the weaving point, means for moving the grippers in a path extending backwardly and downwardly to carry the tuft yarn below the warp and then to return the grippers to their upper position in a path non-intersecting with the path of movement of the weft inserting means that the weft may be inserted in the shed during the return movement of the grippers.

39. In a tuft pile fabric loom, the combination of the lay having dents to beat up the weft, weft inserting means, grippers for taking lengths of tuft yarn from a source of supply, means for moving the grippers in a backward and downward direction to carry the tuft yarn through the warp threads and then return the grippers upwardly in a path non-intersecting with the weft inserting means, and means for moving the dents rearwardly in a path non-intersecting with the path of the weft inserting means that increased speed and production may be secured.

40. In a tuft pile fabric loom, the combination of the lay having dents to beat up the weft, weft inserting means, grippers for taking lengths of tuft yarn from a source of supply, means for moving the grippers in a backward and downward direction to carry the tuft yarn through the warp threads and then return the grippers upwardly in a path non-intersecting with the weft inserting means, means for moving the dents rearwardly in a path non-intersecting with the path of the weft inserting means that increased speed and production may be secured and guiding means for the grippers and dents.

41. In a tuft pile fabric loom, the combination of the lay having dents to beat up the weft, a series of grippers for taking tuft yarns from a source of supply and delivering them at the weaving point, guiding elements for the grippers and dents to direct their movements in laterally separated paths, and guides for the warp threads for directing the warp threads laterally of both dents and grippers.

42. In a tuft pile fabric loom, the combina-

tion of the breast comb, the lay having dents to beat up the weft, grippers for taking lengths of tuft yarn from a source of supply and delivering them at the breast comb, guide plates having guiding portions for the dents and laterally separated guiding portions for the grippers and other guiding portions for the warp threads that the grippers and adjacent dents and warp threads may be directed 10 in non-intersecting paths.

43. In a tuft pile fabric loom having a series of grippers for taking lengths of tuft yarn and delivering them at the weaving point, the combination of gripper guide plates between which the grippers are moved, and means for detachably securing the gripper guides in spaced relation on the loom frame.

44. In a tuft pile fabric loom having a series of grippers for taking up lengths of tuft yarn and delivering them at the weaving point, the combination of gripper guides between which the grippers are moved, toothed plates for spacing the gripper guides, and a lock for detachably securing the gripper guides in the loom frame.

45. In a tuft pile fabric loom, the combination of means for supporting and presenting tuft yarn, grippers for taking lengths of yarn from the presenting means, guides for the tuft yarn and grippers constituted as separate blades, a slide bar for moving the blades into guiding position, a blade spacer separate from the bar and having teeth between which the blades extend and a cover plate for holding the blades in the blade spacer.

46. In a tuft pile fabric loom, the combination of means for presenting tuft yarn, grippers for taking lengths of tuft yarn from the presenting means, guides for the tuft yarn and grippers constituted as separate blades, a slide for moving the blades into guiding position, a blade spacer having front and rear rows of teeth between which the blades extend, and a cover plate for securing the blades and spacer in fixed position on the slide.

47. In a tuft pile fabric loom, the combination of means for presenting tuft yarn, grippers for taking lengths of tuft yarn from the presenting means, guides for the tuft yarn and grippers constituted as separate blades, each provided with a bevelled lower edge, a slide for moving the blades into guiding position, a blade spacer having front and rear rows of teeth between which the blades extend, and a cover plate for securing the blades and spacer in fixed position on the slide.

48. In a tuft pile fabric loom, the combination of tuft yarn presenting means, grippers for taking tuft yarn of said presenting means, a cutter carriage, a cutter mounted on the cutter carriage and normally positioned with its cutting edge inoperative with respect

to the line of cut, and means for causing the cutter to move to cutting position when the carriage is moved transversely of the loom.

49. In a tuft pile fabric loom, the combination of tuft yarn presenting means, grippers for drawing lengths of tuft yarn therefrom, a toothed bar for positioning the tuft yarn to be cut, a cutter normally positioned with its cutting edge in non-cutting relation with the teeth of the said bar that the tuft 75 yarn may enter between the teeth, and means for moving the cutter relative to the toothed bar into cutting position and along the toothed bar to cut the tuft yarn.

50. In a tuft pile fabric loom, the combination of tuft yarn presenting means, grippers for drawing lengths of tuft yarn therefrom, a toothed bar for positioning the tuft yarn to be cut, a cutter mounted for movement relative to the toothed bar to and from 85 cutting position and normally held out of cutting position relative to the teeth of the bar that the tuft yarn may enter between the teeth of the bar, and means for causing the cutter to first move relative to the toothed 90 bar into cutting position and then along said bar to cut the tuft yarn.

51. In a tuft pile fabric loom, the combination of tuft yarn presenting means, grippers for drawing the tuft yarn from said 95 means, a bar extending transversely of the loom and having teeth for positioning the tuft yarn, a cutter carriage movable lengthwise of the toothed bar, a cutter mounted on the carriage for movement relative thereto 100 into and out of cutting position, and means for automatically moving the cutter into cutting position when the carriage is to be moved to cut the yarn and out of cutting position on completion of the cut.

52. In a tuft pile fabric loom, the combination of the lay having a recess, a positioning bar in the bottom of the recess, a series of dents resting on the bottom of the recess and each provided with a notch or recess to straddle the positioning bar, and a locking key 110 for locking the dents from upward movement and in the position defined by the dent positioning bar.

53. In a tuft pile fabric loom, the combination of the lay having a dent receiving recess, a series of dents each having a locking notch at one of its upwardly extending edges, a dent positioning bar in the bottom of the recess of the lay, a locking key having a projecting notch engaging portion for locking the dents from upward movement and in the position defined by the dent positioning bar, and means for securing the locking key releasably in its locking position that any one 120 or more of the dents may be readily removed.

54. In a tuft pile fabric loom, the combination of the lay having a dent receiving recess extending longitudinally thereof, a series of dents having foot portions seated upon 130

the bottom of said recess and provided with a locking notch, a toothed positioning bar at the bottom of said recess for positioning the dents, locking keys of short length each having a projection for engaging the locking notches of the dents and holding the dents in the lay and on the toothed positioning bar, and means for detachably securing each locking key to the lay that any one or more of the 10 dents may be removed by manipulation of its key securing means.

55. In a tuft pile fabric loom, a breast comb formed of separate teeth, a rack secured to the breast beam for relatively positioning the 15 separate teeth forming the breast comb, and means for securing the separate teeth in their assembled relation with the rack.

56. A breast comb for tuft pile fabric looms formed of independently fabricated comb 20 teeth and means for securing the separate teeth in assembled relation to form the complete breast comb.

57. In a tuft pile fabric loom, the combination of the breast beam, a breast comb 25 formed of separate teeth, and means for securing the separate teeth on the breast beam in assembled relation.

58. A breast comb for tuft pile fabric looms formed of separate teeth, each of which is 30 provided with a notched longitudinal edge and means for securing the separate teeth in assembled relation to form the complete breast comb.

59. In a tuft pile fabric loom, the combination of the breast beam having a recess, a positioning rack in the recess of the breast beam, separate breast comb teeth mounted in the rack, and means for securing the separate teeth in assembled relation with the rack to 40 form the complete breast comb.

60. In a tuft pile fabric loom, the combination of tuft yarn presenting means, grippers for drawing tuft yarn therefrom, a bar extending transversely of the loom and having 45 teeth for positioning the tuft yarn to be cut, a cutter for cutting the tuft yarn, and means for causing the grippers to move the tuft yarn held by them in the direction of the toothed bar to place the tuft yarn in the teeth of 50 the bar.

61. In a tuft pile fabric loom, the combination of the gripper shaft having gripper jaws secured thereto, rotatable bearings in which the gripper shaft is eccentrically mounted, 55 gripper closing jaws, a gripper closing shaft carried by the gripper shaft and operatively connected to the gripper closing jaws, means for rotating the gripper closing shaft to grip the tuft yarn, a lock for holding the grippers closed, means for rotating the gripper shaft to carry the gripped tuft yarn backwardly and downwardly through the warp, means for rotating the bearings for raising the closed grippers above the warp threads at the weav- 60

ing point and means for tripping the lock 65 to free the tuft yarn.

62. In a tuft pile fabric loom, the combination of the gripper shaft having gripper jaws secured thereto, rotatable bearings in which the gripper shaft is eccentrically mounted, 70 gripper closing jaws, a gripper closing shaft carried by the gripper shaft and operatively connected to the gripper closing jaws, means for rotating the gripper closing shaft when the grippers are in upper position to grip 75 the tuft yarn, a catch for holding the grippers closed, means for rotating the gripper shaft to carry the grippers through the warp and back to upper position, means for rotating the bearings to raise the grippers from 80 the warp, and a trip arm to trip the catch and free the tuft yarn after the grippers have been raised above the warp at the weaving point.

63. In a tuft pile fabric loom, the combination of the gripper shaft having gripper jaws secured thereto, rotatable bearings in which the gripper shaft is eccentrically mounted, 85 gripper closing jaws, a gripper closing shaft carried by the gripper shaft and operatively 90 connected to the gripper closing jaws, means for rotating the gripper closing shaft when the grippers are in upper position to grip the tuft yarn, a catch for holding the grippers closed, means for rotating the gripper 95 shaft to carry the grippers through the warp and back to upper position, means for rotating the bearings to raise the grippers from the warp before they are returned to upper position, and a trip arm to trip the catch 100 and free the tuft yarn after the grippers have been raised above the warp at the weaving point.

64. In a tuft pile fabric loom, the combination of grippers to take lengths of tuft yarn 105 from a source of supply and deliver them at the weaving point, means for swinging the grippers in a backward and downward path to carry the tuft yarn through the warp and then swing the gripper in a different path 110 backwardly and upwardly, and means for closing and opening the grippers.

65. In a tuft pile fabric loom, the combination of the lay having a dent receiving recess, 115 a positioning bar in the bottom of said recess, a series of dents having upper free ends and each provided with a notch or recess in its bottom edge to straddle the positioning bar, a spacer engaging the dents at the upper portion of said recess, and a locking key for 120 directly engaging and holding the dents in position as defined by the positioning bar and spacer.

In testimony whereof, we have signed our names to this specification.

EDGAR F. HATHAWAY.
WALTER BIXBY.
